(57) **CLAIM**

The ornamental design for a medical implant device, as shown and described.

DESCRIPTION

FIG. 1 is an isometric view of a medical implant device; FIG. 2 is a front elevation view thereof; FIG. 3 is a rear elevation view thereof; FIG. 4 is a top plan view thereof; FIG. 5 is a bottom plan view thereof; FIG. 6 is an elevation view thereof from the right side; and, FIG. 7 is an elevation view thereof from the left side. The broken lines illustrate portions of the medical implant device that form no part of the claimed design.
